J. A. LINSTROM,
LATCH AND LATCH OPERATING MECHANISM,
APPLICATION FILED APR. 3, 1917.

1,280,777.

Patented Oct. 8, 1918.

Fig. 1.

A technical drawing of a mechanical assembly. The drawing shows a base with a hatched pattern. On the base, there is a central vertical structure labeled 24. At the top of this structure is a cross-shaped part labeled 17. A vertical rod labeled 16 is attached to the top of the cross-shaped part. A horizontal rod labeled 15 is attached to the side of the central structure. A horizontal rod labeled 13 is attached to the side of the central structure. A horizontal rod labeled 22 is attached to the side of the central structure. A horizontal rod labeled 10 is attached to the side of the central structure. A horizontal rod labeled 7 is attached to the side of the central structure. A horizontal rod labeled 8 is attached to the side of the central structure. A horizontal rod labeled 21 is attached to the side of the central structure. A horizontal rod labeled 23 is attached to the side of the central structure. A horizontal rod labeled 9 is attached to the side of the central structure. A horizontal rod labeled 1 is attached to the side of the central structure.

ATTORNEY

UNITED STATES PATENT OFFICE.

JOHN A. LINSTROM, OF BANCROFT, NEBRASKA.

LATCH AND LATCH-OPERATING MECHANISM.

1,280,777.

Specification of Letters Patent. Patented Oct. 8, 1918.

Application filed April 3, 1917. Serial No. 159,462.

To all whom it may concern:

Be it known that I, JOHN A. LINSTROM, a citizen of the United States, residing at Bancroft, in the county of Cuming and State of 5 Nebraska, have invented certain new and useful Improvements in Latches and Latch-Operating Mechanism, of which the following is a specification.

My invention relates to latches and a man- 10 ually operable operating mechanism therefor.

The primary object of my present invention is to provide a latch which will effectively retain the door or gate in closed position and which may be readily operated from 15 either side of the door or gate to open the same.

It is another object of my invention to provide a latch and latch operating means 20 which may be easily and readily applied to any gate or door without materially changing the construction.

A further object of my present invention is to provide a latch and mechanism for 25 operating the same which consists of few operating parts, is inexpensive to manufacture, the parts which may be assembled and disassembled and which will be durable and efficient in operation.

30 The above general objects and others will become apparent in the following description and the inventive idea claimed therein and the invention illustrated in the accompanying drawings in which:

35 Figure 1 is a side elevation of a gate or door having my improved latch and operating mechanism mounted thereon.

Fig. 2 is a horizontal sectional view taken on line 2—2 of Fig. 1.

40 Fig. 3 is a vertical sectional view taken on line 2—2 of Fig. 1, and

Fig. 4 is a transverse horizontal view taken on line 4—4 of Fig. 1 and showing the sliding bolt in elevation.

45 Referring to the drawing in which similar reference numerals designate like and corresponding parts throughout all of the views, the numeral 5 designates a gate or door of any desired construction which is provided

50 with an opening 5 and has straps or keepers 7 mounted thereon. A like strap or keeper 8 is mounted on the side of a stationary support 9.

Slidably mounted through the keepers 7

and 8 is a bolt 10 which has one end thereof 55 bent at right angles as at 11 which limits the movement of this bar in one direction. Extending through the opening 6 and rotatably mounted therein is the right angularly disposed end of the operating rod or handle 13 60 formed with an eye 14 at its lower end. This right angularly extending end of the rod 13 has nuts 15 threaded thereon which are engaged with the opposite faces of the gate. This end of the rod 15 extends outwardly for a distance and has connected thereto an operating rod 16 by means of a set screw 17. The lower end of the rod 16 is provided with a ring or eye similar to the 65 ring or eye 14 of the rod 13. 70

Connected with the eye 21 carried by the rod 13 is one end of an expansible spring 32 which has its opposite end connected with the eye 21 secured to the strap 7 at the forward end of the gate 5. The normal tendency of this spring 22 is to urge the bolt 10 toward the keeper 8 and retain the same in locked engagement with this keeper. 75

Mounted on the gate 5 at opposite sides thereof are hasps 23 which are of the usual 80 construction. Locks 24 are adapted to be engaged with these hasps and the eyes formed upon the lower ends of the operating rods or handles 13 and 16.

It will be seen that when it is desired to 85 open the gate from either side thereof, either of the rods or handles 13 and 16 are moved toward the rear end of the gate 5 which will move the link 19 away from the keeper 8 which causes the bolt to be retracted from 90 this keeper 8. Upon releasing the handle or rods 13 and 16 the latch will assume the full line position shown in Fig. 1 owing to action of the coil springs 22.

It will be noted that I have provided a 95 latch and latch operating mechanism that can be locked upon either side of the gate, and when unlocked can be opened from either side. It will also be noted that my improved latch and latch operating mechanism can be operated with little effort and is one which is simple, efficient and durable in use. 100

This disclosure is merely for the purpose of illustration only and it is to be understood 105 that the inventive idea can be carried out in constructions other than the one herein specified. I do not limit myself to the exact

details herein stated but my limitations of modifications are only limited by the here-with appended claims.

What is claimed is:—

- 5 1. The combination with a door of a horizontally sliding bolt, operating levers arranged for swinging movement upon opposite sides of the door and connected together at one end, a link connecting the intermediate portion of said bolt with the intermediate portion of one of said levers, a spring engaging the bolt and normally urging the same to a projected position, and means engageable with the free ends of said levers to retain the levers against swinging movement in a direction to retract said bolt.
- 10 2. The combination with a door, of a sliding bolt, an operating lever mounted for

swinging movement on opposite sides of said door and pivotally connected thereto above said bolt, a link connected at one end to said bolt and at its opposite end to one of the levers below the pivot point thereof, staples extending at right angles from opposite sides of said door below said bolt, eyes formed on the free ends of said levers and arranged to be aligned with said staples, and fastening means insertible through said eyes and staples to lock the bolt in a projected position.

In testimony whereof I affix my signature in presence of two witnesses.

JOHN A. LINSTROM.

Witnesses:

G. L. REBHAUSEN,
G. ARTHUR BAILEY.
